KNURLING DEVICE

Cernyw F. Jones, Economy, Ind., assignor to Perfect Circle Corporation, Hagerstown, Ind., a corporation of Indiana

Application June 11, 1949, Serial No. 98,599

12 Claims. (Cl. 80—5.1)

1

This invention relates generally to a knurling device for knurling the peripheral surface of a cylindrical object and more particularly to a device for knurling predetermined areas on the peripheral surface of a hollow cylindrical article such as a piston for an internal combustion engine.

With continued operation of an internal combustion engine, the pistons and cylinders tend to wear or become distorted with the result that the normal fit of the pistons within the cylinders is lost. This condition is often characterized by "piston slap" and other evidence of excessive looseness. The lack of proper fit between the piston and the cylinder is objectionable since it impairs engine efficiency and has an adverse effect on the economy of operation.

Various means for correcting this condition have been employed, one method involving the expansion of the outer wall or skirt portion of the piston sufficiently to reestablish the normal fit between piston and cylinder. Such expansion may be accomplished, for example, by knurling the outer surface of the piston to form roughened areas on the thrust faces thereof having an interrupted surface comprising projecting portions with intervening depressions. During knurling the metal is extruded or swaged to a sufficient extent so that the projections formed on the piston surface extend outwardly to the desired increased size whereby the proper fit between the piston and the cylinder is realized.

Although during knurling of a piston the work may be supported or stabilized by hand of the operator, it is generally desirable to provide the knurling device with a suitable work-supporting member or structure which results in more effective stabilization of the piston during knurling and also frees both hands of the operator for manipulation of the knurling mechanism proper. Because the normal contour of a piston is slightly oval or out-of-round, it is necessary that such a work support be designed to permit a limited degree of relative movement between the piston and the knurling mechanism in order to compensate for the varying piston diameter. In addition, the knurling mechanism preferably comprises an anvil member or other supporting means adapted to engage and support the piston internally while a knurling element engages the exterior of the piston under pressure. However, the interior surface of the skirt portion of a piston is usually quite uneven in the area between the wrist pin bosses because of various protuberances and surface irregularities such as reinforcing ribs, partial machining of the interior

2

surface, and general surface roughness characteristic of cast articles. Thus, the problem is presented of providing a knurling device which will readily accommodate the variations in piston wall thickness while at the same time avoiding any substantial change in knurling pressure against the outer surface of the piston.

Accordingly, one object of my invention is to provide a device for knurling the exterior surfaces of pistons which readily accommodates variations in piston wall thickness while maintaining a substantially constant knurling pressure.

Another object of my invention is to provide a device for knurling the exterior surfaces of pistons in which a supporting member engages the interior of the piston, a knurling member engages the exterior of the piston, and the spacing between said members is permitted to vary automatically to accommodate protuberances and other irregularities on the interior surface of the piston.

An additional object of the invention is to provide a simple hand-operated device for knurling the exterior surfaces of pistons in combination with a novel work support adapted to stabilize the piston in both horizontal and vertical planes during knurling.

A further object of the invention is to provide a device for knurling the exterior surfaces of pistons, said device having manually operable means for adjustably spacing the knurled areas axially of the piston.

Other objects and advantages of the invention will become apparent from the subsequent detailed description of the invention and the accompanying drawings, in which:

Fig. 1 is a front elevational view of a knurling device comprising one specific embodiment of my invention;

Fig. 2 is a fragmentary top plan view of the device shown in Fig. 1;

Fig. 3 is a fragmentary vertical sectional view taken along the line 3—3 of Fig. 1;

Fig. 4 is an end view of the device when viewed from the left in Fig. 1; and

Fig. 5 is an end view of the device when viewed from the right in Fig. 1 with portions thereof in section.

As heretofore mentioned, the knurling device comprising the present invention is provided with a pair of cooperating anvil and knurling elements, the anvil element being arranged to support the piston internally while the knurling element bears against the outer surface of the piston. The knurling element is preferably in the form of a small roller which is applied to the outer surface

of the piston in rolling relation therewith so that the resultant area knurled in one application of the tool comprises a band having a width equal to the width of the roller. Usually the roller is relatively narrow and traverses the piston circumferentially so that a plurality of such knurled bands are required to cover a desired area longitudinally of the piston. The knurled bands may, of course, be disposed in continuous abutting relation to one another or they may be slightly spaced from each other longitudinally of the piston.

With a piston for an internal combustion engine, it is necessary to knurl only the thrust faces of the piston skirt, i. e. those portions which are subjected to lateral thrust against the cylinder wall due to the position of the connecting rod. Thus, the knurling operation may be restricted to the portions of the piston skirt lying intermediate the wrist-pin holes on opposite sides of the piston. The knurled area preferably starts immediately below the ring grooves at the upper end of the piston and may extend axially or longitudinally for the full length of the piston skirt. If desired, the knurled band at the extreme outer end of the skirt may be spaced differently from the remaining bands in order to position the outermost band as close as possible to the edge of the piston.

In addition to effecting expansion of the piston metal by extrusion thereof, in the manner hereinbefore described, whereby to reestablish a proper fit between the piston and the cylinder, the knurled surface obtained by my invention also offers other important advantages. For example, it has been found that better performance is obtained in a reciprocating piston and cylinder, or other like construction, if one of the two surfaces is of an interrupted nature comprising projecting portions with intervening depressions, such as may be provided by knurling. A surface of this character has been found to run cooler than an absolutely smooth surface for pistons as well as other cylindrical objects adapted to reciprocate within a bore. Another advantage inherent in knurling the surfaces of pistons and like articles is found in the improved wearing qualities of the knurled surface resulting from the hardening effects of cold working the metal. In addition, the interrupted surface afforded by knurling provides a series of pockets or reservoirs which serve to retain lubricating oil and thereby maintain a continuous supply of lubricant at the surface contacting areas.

It will be apparent that, in addition to the obvious utility of knurling old or worn pistons in order to expand the same, knurling may also be resorted to in the case of new pistons or original assemblies of pistons within their cylinders in order to attain the other advantages mentioned above. While the knurling device comprising the present invention is designed primarily for knurling pistons, the invention is not limited in this manner but embraces the knurling of the peripheral surfaces of hollow cylindrical articles generally.

The term "knurling" as used throughout the specification and the claims is not limited to the ordinary form of knurling involving grooves arranged in a criss-cross pattern, but rather is used in a broad sense to include any surface formation involving alternate depressed and raised portions regardless of whether one or the other or both of said portions are continuous throughout the area having such formation.

Thus, the term includes not only the criss-cross pattern but also a pattern formed by parallel grooves or by isolated indentations resulting in connected raised portions.

As hereinbefore mentioned, an important object of my invention is to provide a knurling device for pistons which is designed to accommodate varying piston wall thicknesses due to internal protuberances or surface irregularities while at the same time avoiding substantial changes in knurling pressure and eliminating the need for manually adjusting or regulating the device during a knurling operation. I accomplish this end broadly by providing a rigidly mounted knurling member and a cooperating anvil member connected for pivotal movement toward and away from the knurling member, in combination with a spring means for yieldingly urging the anvil member toward the knurling member. The yieldable urging of the one member toward the other permits a variation in spacing between the members upon contact of the anvil member with protuberances on the interior surface of the piston skirt while the knurling member bears with substantially constant pressure against the exterior surface of the skirt.

Referring now to the drawings, which show by way of illustration one specific embodiment of my invention, the device is provided with a rectangular base 25 having at each of its opposite ends a pair of apertured lugs 26 for screwing or bolting the device to a bench surface or other suitable support. Extending upwardly at one end of the base 25 is a work-supporting structure, indicated generally at 27, which comprises an upright post 28 rigidly fastened to the base at the rear thereof, as by means of a plurality of screws 29 (Fig. 4). A pair of upper and lower stabilizing arms, 31 and 32, respectively, project forwardly from the post 28 and are adapted to receive a piston 33 diametrically therebetween and to support the same longitudinally above the base 25, as described hereinafter in detail.

For supporting the knurling mechanism proper, a carriage 34 is slidably mounted on the base 25 and is operatively connected thereto, by means hereinafter described in greater detail, for movement longitudinally of the piston 33 toward and away from the work supporting structure 27. At one end of the carriage 34 nearest the post 28 is an upright knurl support in the form of a bracket 36 having a knurling roller 37 journaled at the upper end thereof. The roller 37 is rotatably mounted on the bracket 36 by means of a pair of bearing sleeves 38 (Fig. 1) keyed to the roller 37, the bearing sleeves 38 and the knurling roller 37 being clamped together and secured to the end of a drive shaft 39 by means of a stud 41 extending longitudinally through the sleeves and the roller and threaded into the end of the shaft 39. A nut 42 is secured at the outer end of the stud 41 for retaining the sleeves 38 and the roller 37 in clamped relation. The drive shaft 39 extends longitudinally of the carriage 34 and is journaled and supported at its opposite end by a bearing bracket 43 extending upwardly at the other end of the carriage 34 remote from the post 28. The bearing bracket 43 is rigidly fastened to the carriage 34 by means of a pair of screws 44. A hand crank 46 extends through an aperture adjacent the end of the drive shaft 39 for manually driving the knurling roller 37 and is adjustably secured thereto by means of a set screw 47.

To provide an anvil support, an upright slightly

curved lever or bracket 48 is fastened at its lower end to a pivot shaft 49 by means of a screw 51, the shaft 49 being journaled in an integral bearing portion 52 at the rear of the carriage 34 and extending longitudinally thereof. An elongated anvil-supporting arm 53 extends laterally from the upper end of the bracket 48 in a direction generally parallel to the drive shaft 39, the arm 53 being fastened to the upper end of the bracket 48 by means of a pair of screws 54 (Fig. 2). The outermost end of the arm 53 is provided with a pair of spaced projections between which is mounted for free rolling movement an anvil member in the form of a hard smooth surfaced roller 56 having approximately the same diameter and width as the knurling roller 37. The anvil roller 56 rotates on a shaft or pin 57 and is urged outwardly of the arm 53 by means of a coil spring 58 encircling the pin 57 whereby the anvil roller 56 is normally maintained in radial alignment with respect to the knurling roller 37 but can be displaced axially thereof in the event that the anvil roller encounters an internal ridge or other circumferential projection on the interior of the piston.

It will be seen that by rotary or rocking movement of the pivot shaft 49 carrying the upright bracket 48, the arm 53 and the anvil roller 56 carried thereon may be moved away from and toward the knurling roller 37. During a knurling operation, the skirt portion of the piston 33 is clamped between the two rollers, the anvil roller 56 being disposed against the interior surface of the piston skirt and the knurling roller 37 bearing against the outer periphery of the piston skirt with the axes of the rollers being parallel to the axis of the piston. As the knurling roller 37 is driven by operation of the hand crank 46, the piston 33 also rotates about its axis in rolling relation to the roller 37 which is in tight engagement therewith.

The pivot shaft 49 is provided with an end portion 59 of reduced diameter (Fig. 1) which extends from the end of the bearing portion 52 adjacent the bracket 36. For rocking the shaft 49, a relatively short lever 61 is provided in the form of a U-shaped member having a base portion 62 and a pair of upright spaced arms indicated at 63. The base portion 62 of the lever 61 is rigidly secured to the projecting end portion 59 of the shaft 49 for rotation therewith and a swivel or rotatable pin 64 extends between the upper ends of the arms 63.

A horizontally disposed spring loading device, indicated generally at 66, coacts with the swivel 64 for applying adjustable yielding pressure against the lever 61 in order to urge the anvil roller 56 toward the knurling roller 37 by rocking movement of the pivot shaft 49 and the bracket 48 carried thereon. To this end, an elongated stud 67 having terminally threaded portions extends longitudinally between the arms 63 of the lever 61 and through a transverse aperture 68 in the swivel 64 (Fig. 3). A screw 69, of larger diameter than the stud 67 and having a manually operable head portion 71, extends from the front of the device through an enlarged concentric bore 72 in the bracket 36 and is threaded in a swivel 73 which is in the form of a shaft rotatably supported in the bracket 36 transversely of the bore 72. The forward end of the stud 67 is tightly connected to the inner end of the screw 69, as by an internally threaded axial bore 74 in the screw 69 which receives the threaded end of the stud 67. Thus, the screw

69 is in effect integral with the stud 67. The screw 69 being of larger diameter than the stud 67, the annular end face of the screw 69 at its juncture with the stud 67 forms a shoulder, as indicated at 76, which is adapted to coact with a flattened recess 77 cut out of the periphery of the swivel 64 opposite the shoulder 76.

Encircling the stud 67 is a helical spring 78 adapted to apply yielding pressure against the swivel 64 through a thrust collar comprising a sleeve 79 carried on the stud 67 and having a flanged end 81 bearing against one end of the spring 78. The flange 81 is adapted to operatively engage the swivel 64 and for this purpose is received within a flattened recess 82, similar to the recess 77, on the opposite side of the swivel 64. A spring load adjusting nut 83 (Fig. 5) is threaded on the opposite or rear end of the stud 67 and bears against the opposite end of the spring 78 through a thrust bearing 84 and a thrust collar comprising a sleeve 86 having a flanged end 87, similar to the sleeve 79 and flange 81.

By adjusting the nut 83, the tension of the spring 78 can be regulated to control the pressure exerted on the lever 61 through the swivel 64 and thereby regulating the knurling pressure, i. e. the pressure under which the skirt portion of the piston 33 is pressed against the knurling roller 37 by means of the internal anvil roller 56. A jam or lock nut 88 is carried on the stud 67 adjacent the adjusting nut 83 for locking the latter in place after the tension of spring 78 has been adjusted to any desired extent.

The operation of the spring loading device 66 is as follows: In the position shown in Figs. 3 and 5, the screw 69 has been screwed outwardly through its threaded connection with the swivel 73 a sufficient distance so that a slight clearance, indicated at 89 in Fig. 3, is established between the shoulder 76 at the inner end of the screw 69 and the recess 77 in the swivel 64. Thus, the full pressure of the spring 78 is brought to bear on the shaft 64 thereby urging the lever 61 in a counterclockwise direction, as viewed in Figs. 3 and 5, and urging the shaft 49 and the bracket 48 in a similar direction whereby the anvil roller 56 is pressed toward the knurling roller 37 with the skirt portion of the piston 33 being clamped therebetween. As described above, the knurling pressure may be controlled by adjusting the nut 83 to regulate the tension of the spring 78.

By means of the operating head 71 on the screw 69 at the front of the device, the screw 69 may be screwed inwardly through the swivel 73 until the shoulder 76 abuts the recess 77 in the swivel 64 thereby rendering the spring load ineffective when the clearance 89 is taken up. At this point, continued inward movement of the screw 69 causes the lever 61 to be rocked in a clockwise direction, as viewed in Figs. 3 and 5, and the anvil roller 56 is thereby disengaged from the interior surface of the skirt portion of the piston 33 as the bracket 48 rocks in a similar direction with the pivot shaft 49. With the rollers 37 and 56 in radially spaced position, the carriage 34 may be moved axially of the piston 33, by means hereinafter described in detail, to position the knurling mechanism at any desired location longitudinally of the piston.

As the lever 61 swings in an arcuate path during movement of the anvil roller 56 to released position, the rear end of the stud 67 and its integrally connected screw 69 pivot

downwardly slight, as viewed in Figs. 3 and 5, in the plane of the bracket 36. To accommodate this pivotal movement of the stud 67 and the screw 69, the swivel 73 and the swivel 64 rotate freely in their respective supporting structures, the bifurcated relation of the arms 63 on the lever 61 and the enlarged bore 72 in the bracket 36 providing sufficient clearance to permit the stud 67 and the screw 69 to assume the necessary angular position.

During the inward movement of the screw 69 as described above, the tension setting of the spring 78 is not disturbed materially since the spring tension is determined by the relative position of the adjusting nut 83 on the stud 67. Inward movement of the screw 69 from the position shown in Figs. 3 and 5 until the clearance 89 is taken up will result in a very slight decrease in the spring tension setting, equivalent to the extent of the clearance 89, but this change is of no practical consequence. Thus, it will be seen that the anvil roller 56 can be backed away from the interior of the piston 33 without unloading the spring 78 or otherwise changing the spring tension setting.

To return the device to knurling position, the screw 69 is operated in reverse fashion whereby to move the same forwardly of the device and of the swivel 73. The tension of the spring 78 acting on the swivel 64 pivots the lever 61 and its associated shaft 49 and bracket 48 whereby to swing the anvil roller 56 into contact with the inner surface of the skirt portion of the piston 33. Upon continued backing away of the screw 69, the shoulder 76 is disengaged from the recess 77 and the roller 56 is urged against the piston 33 with sufficient pressure to sink the ridges on the knurling roller 37 into the outer surface of the skirt. Further movement of the bracket 48 and lever 61 is prevented, and forward movement of the screw 69 is then continued until the slight clearance 89 is reestablished between the recess 77 and the shoulder 76. Thus, the spring 78 is returned substantially to its original tension and the full spring load is again imposed on the swivel 64. Once the clearance 89 is obtained, further operation of the screw 69 is unnecessary since the establishment of the slightest clearance at this point permits the full spring tension, as determined by the setting of the nut 83, to be applied against the swivel 64.

As hereinbefore mentioned, the carriage 34 is movable relative to the base 25 and longitudinally of the piston 33 in order to provide the latter with a plurality of axially spaced knurled bands or tracks while the piston 33 is held longitudinally above the base 25 by the work-supporting structure 27. For effecting movement of the carriage 34 along the base 25 away from and toward the work-support 27, a rack 90 is mounted on the base, with its teeth extending upwardly therefrom and is slidably received within an elongated groove or slideway 91 (Figs. 4 and 5) at the under side of the carriage 34. The rack 90 thus functions as a guide for the carriage as the latter travels on the base 25. The carriage 34 is provided with a rearwardly extending boss 92 (Fig. 2) having a pinion shaft 93 (Fig. 5) journaled therein and carrying a pinion 94 at its inner end for engaging or meshing with the teeth of the rack 90. A hand wheel 96 is secured to an extension 97 of reduced diameter at the front end of the pinion shaft 93 for rotating the pinion 94 and 75

thereby effecting movement of the carriage 34 in either direction relative to the rack 90. A retaining collar or yoke 98 is disposed around the extension 97 between the hand wheel 96 and the pinion shaft 93 and is fastened to the boss 92 by means of a screw 99.

In order to clamp the carriage 34 in place at any desired position relative to the rack 90, a stud 101 (Fig. 1) depends from an ear 102 10 on the carriage 34 and extends through an elongated slot 103 (Fig. 5) in the base 25 parallel to the rack 90. A clamping nut 104 is threaded to the lower end of the stud 101 at the under side of the base 25 and is provided with a handle 106 extending forwardly beyond the base. In order to hold the carriage 34 in snug but 15 movable relation with the base 25 when the clamping nut 104 is loosened preparatory to effecting travel of the carriage 34, a retaining washer 107 is disposed on the stud 101 between the clamping nut 104 and the under side of the base 25 and a helical spring 108 (Fig. 1) is provided in an internal recess 109 in the nut 104 for exerting pressure between the clamping nut 20 104 and the washer 107.

During a knurling operation the peripheral surface of the piston 33 is held squarely against the face of the knurling roller 37 by means of the 25 clamping action of the anvil roller 56 forcing the piston skirt against the knurling roller. However, an important feature of my invention is the work-supporting structure 27, hereinbefore briefly described, which stabilizes and supports the piston 33 in a vertical direction during knurling. 30 The piston 33 is retained with its axis horizontal above the base 25 between the stabilizing arms 31 and 32 which extend forwardly from the post 28 and are vertically spaced from each other substantially the diameter of the piston. The lower 35 stabilizing arm 32 is adjustably mounted on the post 28 by means of a socket portion 110 in slidable engagement with the post 28. For holding the arm 32 squarely and rigidly on the post 28, an elongated key 111 (Fig. 1) fits into a longitudinal groove or keyway 112 in the side of the post 28 and extends into a complementary groove or keyway 112' in the socket 110. A clamping screw 113 extends through one side of the socket 110 and engages a cone socket, indicated at 113', provided in the key 111 for securing the arm 32 40 at any desired elevation above the base 25.

Because of the normal oval or out-of-round contour of a piston, the upper stabilizing arm 31, while adapted to be generally fixed relative to the post 28, is also flexibly or resiliently mounted 45 in order to accommodate the varying piston diameter as the piston 33 rotates on its axis between the arms 31 and 32 upon driving of the knurling roller 37. In order to provide this desired flexibility or relative movement between the arms 31 and 32, the upper stabilizing arm 31 is movably mounted on the post 28 and having an internal diameter slightly greater than the diameter of the post 28 in order to provide a slight clearance or loose fit therebetween. A clamping screw 115 extends through the side of the socket 114 and is provided at its inner end with a conical point (Figs. 1 and 2) for engaging a key 116 fitting snugly in the groove 112. A complementary pivot member in the form of a conically pointed set screw 118 extends through the socket 114 opposite the screw 116 and engages a key 117 fitting snugly in an elongated groove 119, similar to the groove 112, on the opposite side of the post 28. The socket portion 114 is provided with corre-

sponding keyways to receive the keys 116 and 117 but these keyways are slightly wider than the keys. A helical spring 121 (Fig. 4) is disposed in a bore 122 in the arm 31 at the inner end thereof adjacent the socket 114 and bears against the post 28 above the pivot screws 116 and 118 whereby to urge the arm 31 downwardly as a result of the pivotal connection of the latter with the post 28. Thus, the arm 31 may be positioned on the post 28 at any desired spacing above the arm 32, dependent upon the size of the piston being knurled, while at the same time, because of the clearance between the post 28 and the socket portion 114 and because the keyways in the socket portion 114 are slightly wider than the keys 116 and 117, the pivot screws 116 and 118 permit limited pivotal movement of the arm 31 relative to the post 28.

Because of the spring-pressed relation of the arm 31 against the exterior of the piston 33, the arm 31 may pivot upwardly and downwardly relative to the arm 32 as the effective diameter of the piston 33 varies slightly during rotation of the latter about its axis. Thus, it will be seen that the work-supporting structure 27 of my device effectively stabilizes the piston 33 in a vertical direction while at the same time permitting the necessary degree of movement of the piston because of its oval form. In addition, the spring-pressed relation of the arm 31 against the piston 33 also permits the piston to rotate freely during knurling and to slide horizontally between the two stabilizing arms as the anvil roller 56 is swung into engagement with the interior of the piston skirt and presses the latter against the knurling roller 37 at the beginning of a knurling operation.

A key in the form of a relatively thin plate 123 is fastened adjacent the bottom edge of the arm 31 by means of a plurality of screws 124. As best seen in Fig. 1, the key 123 extends below the arm 31 and is adapted to be received within one of the piston grooves in order to prevent any tendency toward endwise movement or longitudinal displacement of the piston 33 during operation of the device.

In knurling a piston with the device shown in the drawings, the piston 33 is first mounted in clamped relation between the stabilizing arms 31 and 32 of the work-supporting structure 27 with the key 123 being received in one of the ring grooves of the piston in order to prevent endwise movement of the piston during knurling. During the mounting of the piston in the work-supporting structure 27, the carriage 34, having the knurling mechanism proper mounted thereon, is positioned at the far end of the base 25 free of the skirt portion of the piston. The elevation of the piston 33 with respect to the base 25 is adjusted so that the axis of the piston is in substantially the same horizontal plane as the axes of the knurling roller 37 and the anvil roller 56. The horizontal position of the piston 33 relative to the post 28 is also adjusted by sliding the piston between the arms 31 and 32 away from or toward the post 28 as required so that the skirt portion of the piston will clear the knurling roller 37 to permit the latter to engage the outer periphery of the skirt.

With the bracket 48 in released position so that the rollers 37 and 56 are in spaced relation, the hand wheel 96 is actuated to effect movement of the carriage 34 toward the open end of the piston. During travel of the carriage 34, the clamping nut 104 is, of course, loosened slightly and the spring loaded washer 107 maintains the carriage

34 snugly against the base 25 while at the same time permitting sliding movement thereof. The carriage 34 is moved toward the piston 33 until the skirt extends between the rollers 37 and 56 to the desired extent, and at this point the carriage 34 is clamped securely in place on the base 25 by tightening the clamping nut 104. Upon adjustment of the nut 83 to obtain the desired tension in the spring 18 and upon backing away of the screw 69 to return the bracket 48 to operating position, the desired knurling operation may then be carried out by rotating the hand crank 46 which drives the knurling roller 37.

Rotation of the hand crank 46 results in relative rolling movement between the knurling roller 37 and the piston 33 circumferentially of the latter. Because the skirt portion of the piston 33 is clamped between the rollers 37 and 56, rotation of the knurling roller 37 also causes simultaneous rotation of the piston about its axis whereby to form an arcuate knurled band on the outer periphery of the skirt, as hereinbefore described. As a result of the pivoted mounting 25 of the upper stabilizing arm 31 on the post 28 and the spring-pressed relation thereof with respect to the piston 33, the arm 31 pivots up and down as it rides on the periphery of the piston and thereby accommodates the variations in piston diameter as the latter rotates between the arms 31 and 32. During knurling the piston is stabilized in all directions by the clamping action of the rollers 56 and 37, by the clamping action of the arms 31 and 32, and by the retaining action of the key 123.

During the course of a knurling operation if the anvil roller 56 encounters internal protuberances or other surface irregularities on the interior of the piston skirt, it will be seen that the yielding application of the anvil roller 56, by the spring loading device 66, against the inner surface of the piston skirt permits the roller 56 to be forced away from the protuberance, the bracket 48 rocking in a clockwise direction (as viewed in Figs. 3 and 5) along with the pivot shaft 49 and the lever 61. The slight compression of the spring 18 resulting from such rocking movement as the lever 61 is forced rearwardly of the device against the action of the spring 18 will have no significant effect on the pressure with which the skirt portion of the piston 33 is clamped between the rollers 37 and 56. Thus, my device provides for substantially constant knurling pressure, as predetermined by the setting of the adjusting nut 83 and the lock nut 88, even when the radial spacing between the rollers 37 and 56 varies as the anvil roller 56 passes over surface irregularities on the interior of the piston skirt.

As hereinbefore mentioned, the diameters and widths of the knurling roller 37 and the anvil roller 56 are preferably substantially the same. Such a relationship insures that the anvil roller will have an area of engagement with the interior 65 of the piston skirt which lies substantially within the area of engagement of the knurling roller with the exterior of the skirt, thereby avoiding any possibility of undesired peripheral distortion of the piston skirt as a result of the pressure between the knurling and anvil rollers. Of course, the swaging action of the knurling roller results in an increase in the diameter of the piston skirt, as hereinbefore described.

Although the invention has been described in detail with reference to one specific structural

embodiment, it will be understood that various modifications and equivalent structures may be resorted to without departing from the scope of the invention as defined in the appended claims.

I claim:

1. Knurling means for a device for knurling the thrust faces of the skirt portion of a piston, comprising a base, a carriage slidably mounted on said base for movement longitudinally of the piston, knurling mechanism supported on said carriage and comprising a knurling roller adapted to engage the exterior surface of the piston skirt and an anvil member adapted to support the skirt interiorly thereof, and actuating means for effecting travel of said carriage along said base, said actuating means comprising a rack mounted on the upper surface of said base and the under side of said carriage having a groove in which the rack is slidably received whereby to guide the travel of said carriage on said base, and a manually operable pinion mounted on said carriage and meshing with said rack.

2. Knurling means for a device for knurling the thrust faces of the skirt portion of a piston, comprising a base having an elongated rack at the upper surface thereof and an elongated slot parallel to said rack, a carriage slidably disposed on said base for movement longitudinally of the piston, knurling mechanism mounted on said carriage and comprising a knurling roller adapted to engage the exterior surface of the piston skirt and an anvil member for engaging the skirt interiorly thereof, a manually operable pinion journaled in said carriage in operative engagement with said rack, a stud extending downwardly from said carriage through said slot, a clamping nut threaded on the lower end of said stud for clamping said carriage to said base, and a spring coacting between said nut and the under side of said base for retaining said carriage in movable engagement with said base when said clamping nut is loosened to permit travel of said carriage.

3. A device for knurling the thrust faces of the skirt portion of a piston of slightly oval shape, comprising a base, a work support on said base for holding a piston thereabove during knurling and for stabilizing the piston during rotation thereof on its axis, and knurling mechanism slidably mounted relative to said base for movement away from and toward said work support longitudinally of the piston and comprising a pair of members adapted to clamp the wall of the piston therebetween with one of said members being rotatable to rotate the skirt of the piston therebetween, said work support comprising an upright post at one end of said base and a pair of upper and lower stabilizing arms mounted on said post for vertical adjustment and extending outwardly therefrom for receiving the head end of the piston diametrically therebetween, one of said arms being mounted for limited pivotal movement relative to said post whereby to accommodate the varying diameter due to the oval shape of the piston as the latter rotates on its axis between said arms.

4. A device for knurling the thrust faces of the skirt portion of a piston of slightly oval shape, comprising a base, a work support on said base for holding a piston thereabove during knurling and for stabilizing the piston during rotation thereof on its axis, knurling mechanism slidably mounted relative to said base for movement away from and toward said work support longitudinally of the piston and comprising

ing a pair of members adapted to clamp the wall of the piston therebetween with one of said members being rotatable to rotate the skirt of the piston therebetween, said work support comprising an upright post at one end of said base,

5 a pair of upper and lower stabilizing arms mounted for vertical adjustment on said post and extending outwardly therefrom for receiving the head end of the piston diametrically therebetween, one of said arms being mounted for limited pivotal movement relative to said post whereby to accommodate the varying diameter due to the oval shape of the piston as the latter rotates on its axis between said arms, and spring means for yieldingly urging said one arm into contact with the piston.

6. A device for knurling the thrust faces of the skirt portion of a piston of slightly oval shape, comprising a base, a work support on said base for holding a piston thereabove during knurling and for stabilizing the piston during rotation thereof on its axis, knurling mechanism slidably mounted relative to said base for movement away from and toward said work support longitudinally of the piston and comprising a pair of members adapted to clamp the wall of the piston therebetween with one of said members being rotatable to rotate the skirt of the piston therebetween, said work support comprising an upright post at one end of said base, a pair of upper and lower stabilizing arms mounted for vertical adjustment on said post and extending outwardly therefrom for receiving the head end of the piston diametrically therebetween, said upper arm being secured to said post by means including a pair of pivot members whereby said upper arm is mounted for limited pivotal movement relative to said post for accommodating the varying diameter due to the oval shape of the piston as the latter rotates on its axis between said arms, and a helical spring coacting between the inner end of said upper arm and said post above said pivot members for yieldingly urging the outer end of said upper arm into contact with the piston.

6. A device for knurling the thrust faces of the skirt portion of a piston of slightly oval shape, comprising a base, a work support on said base for holding a piston thereabove during knurling and for stabilizing the piston during rotation thereof on its axis, knurling mechanism slidably mounted relative to said base for movement away from and toward said work support longitudinally of the piston and comprising a pair of members adapted to clamp the wall of the piston therebetween with one of said members being rotatable to rotate the skirt of the piston therebetween, said work support comprising an upright post at one end of said base, a pair of upper and lower stabilizing arms mounted for vertical adjustment on said post and extending outwardly therefrom for receiving the head end of the piston diametrically therebetween, one of said arms being mounted for limited pivotal movement relative to said post whereby to accommodate the varying diameter due to the oval shape of the piston as the latter rotates on its axis between said arms, and a retaining member projecting from one of said arms and adapted to be received within a ring groove of the piston for preventing endwise movement of the latter during knurling.

7. A knurling means for a device for knurling the thrust faces of the skirt portion of a piston, comprising a carriage slidably mounted for

movement longitudinally of the piston, a knurling roller rigidly supported in elevated position above said carriage at one end thereof and adapted to be positioned in engagement with the exterior surface of the skirt, driving means operatively connected with said knurling roller for effecting relative rolling movement between said roller and the skirt circumferentially of the latter, a pivot shaft journaled on said carriage and extending longitudinally thereof, an upright bracket carried on said pivot shaft at the opposite end of said carriage, an elongated anvil-supporting arm extending from said bracket longitudinally of said carriage and carrying an anvil member at the outer end thereof for engaging the interior of the skirt substantially in alignment with the knurling roller radially of the piston, an upright lever on said pivot shaft, and spring means operatively engaging said lever for yieldingly urging said anvil member toward said knurling roller.

8. Knurling means for a device for knurling the thrust faces of the skirt portion of a piston, comprising a carriage slidably mounted for movement longitudinally of the piston, a knurling member in the form of a roller rigidly supported in elevated position above said carriage at one end thereof and adapted to be positioned in engagement with the exterior surface of the skirt, driving means operatively connected with said knurling roller for effecting relative rolling movement between said roller and the skirt circumferentially of the latter, a pivot shaft journaled on said carriage and extending longitudinally thereof, an upright bracket carried on said pivot shaft at the opposite end of said carriage, an elongated anvil-supporting arm extending from said bracket longitudinally of said carriage and carrying an anvil member at the outer end thereof for engaging the interior of the skirt substantially in alignment with the knurling roller radially of the piston, an upright lever on said pivot shaft, and spring means coacting with said lever for yieldingly urging said anvil member toward said knurling member, said spring means including tension adjusting means for varying the pressure between said members and manually operable releasing means for actuating said lever in the opposite direction against the spring action without substantially altering the tension of said spring means whereby to release the spring pressure urging the anvil member toward the knurling member and thereby permit disengagement of said members from the surfaces of the skirt.

9. Knurling means for a device for knurling the thrust faces of the skirt portion of a piston, comprising a carriage slidably mounted for movement longitudinally of the piston, an upright knurl support rigidly secured to said carriage at one end thereof, a knurling roller journaled at the upper end of said knurl support and adapted to be positioned in engagement with the exterior surface of the skirt, driving means operatively connected with said knurling roller for effecting relative rolling movement between said roller and the skirt circumferentially of the latter, a pivot shaft journaled on said carriage and extending longitudinally thereof, an upright bracket carried on said pivot shaft at the opposite end of said carriage, an elongated anvil-supporting arm extending from said bracket longitudinally of said carriage and carrying an anvil member at the outer end thereof for engaging the interior of the skirt substantially in alignment with the knurling roller radially of the piston, an upright

lever on said pivot shaft adjacent said knurl support, and spring means coacting with said knurl support and with said lever for yieldingly urging said anvil member toward said knurling roller.

- 5 10. Knurling means for a device for knurling the thrust faces of the skirt portion of a piston, comprising a carriage slidably mounted for movement longitudinally of the piston, an upright knurl support rigidly secured on said carriage at one end thereof, a knurling roller journaled at the upper end of said knurl support and adapted to engage the exterior surface of the skirt, driving means operatively connected with said knurling roller for effecting relative rolling movement between said roller and the skirt circumferentially of the latter, a pivot shaft journaled on said carriage and extending longitudinally thereof, an anvil member adapted to engage the interior of the skirt substantially in alignment with the knurling roller radially of the piston, supporting structure for said anvil member carried on said pivot shaft at the opposite end of said carriage for movement of said anvil member away from and toward said knurling roller upon rocking movement of said pivot shaft, an upright lever on said pivot shaft adjacent said knurl support, and adjustable spring loading means operatively associated with said supporting structure for yieldingly urging said anvil member toward said knurling roller whereby said roller and said anvil member are pressed against the respective surfaces of the skirt under a predetermined substantially constant pressure, said spring loading means comprising an elongated member extending transversely through said knurl support adjacent the upper end of said lever, a helical spring carried concentrically on said elongated member for urging said lever in a direction to move said anvil member toward said knurling roller, means 40 cooperating with said elongated member for adjusting the tension of said spring, and means on said elongated member for operatively engaging said lever for urging the same in the opposite direction against the action of said spring whereby 45 to swing said anvil member away from said knurling roller without substantially altering the tension of said spring.

11. Knurling means for a device for knurling the thrust faces of the skirt portion of a piston, comprising a carriage slidably mounted for movement longitudinally of the piston, an upright knurl support rigidly mounted on said carriage at one end thereof and having an enlarged bore extending transversely therethrough, a knurling roller journaled at the upper end of said knurl support and adapted to be positioned in engagement with the exterior surface of the skirt, driving means for effecting relative rolling movement between said knurling roller and the skirt circumferentially of the latter, a pivot shaft journaled on said carriage and extending longitudinally thereof, an anvil member adapted to engage the interior of the skirt substantially in alignment with the knurling roller radially of the piston, supporting structure for said anvil member carried on said pivot shaft adjacent the opposite end of said carriage for movement of said anvil member away from and toward said knurling roller upon rocking movement of said pivot shaft, an upright lever having a bifurcated upper end mounted at the opposite end of said pivot shaft adjacent said knurl support, a swivel journaled in said knurl support and extending transversely of said bore, a second swivel journaled between the bifurcated portions of said

lever, and a spring loading device coacting with said swivels and extending through said bore and said bifurcated end for urging said anvil member toward said knurling roller, said device including manual means for shifting said anvil member into and out of coacting relation with said knurling roller by pivotal movement of said lever, and said bore and the bifurcated upper end of said lever providing sufficient clearance to permit pivotal movement of said device upon 10 pivotal movement of said lever.

12. A device for knurling the thrust faces of the skirt portion of a piston, comprising a knurl support, a knurling roller journaled at one end of said knurl support and adapted to engage the 15 exterior surface of the skirt, an anvil member adapted to engage the interior of the skirt, supporting structure for said anvil member mounted in pivotal relation to said knurl support for movement of said anvil member away from and toward said knurling roller, an actuating lever operatively associated with said supporting structure for effecting pivotal movement thereof, a swivel journaled in said knurl support, a second swivel journaled in said lever, an elongated member threaded transversely through said first-named swivel and extending transversely through 20 said second-named swivel in slidable relation therewith, a helical spring encircling said elongated member at one end thereof adjacent said second-named swivel, said second-named swivel being operatively engaged at one side thereof

with said spring for urging said lever toward said knurl support and urging said anvil member toward said knurling roller, said elongated member having a shoulder portion at the opposite side of 5 said second-named swivel for engaging the latter whereby to urge said lever in the opposite direction against the action of said spring, and manually operable means for rotating said elongated member at its threaded connection with said first-named swivel for moving said shoulder portion into and out of engagement with said second-named swivel.
